Cleveland, Ohio 44111

Filed Oct. 20, 1972, Ser. No. 299,253

Term of patent 14 years

Int. Cl. D6—06

U.S. Cl. D6—114

FIG. 1 is a perspective view of a display and demonstrator rack for cylindrical locksets and the like, showing my new design;

FIG. 2 is a plan view thereof; and

FIG. 3 is a side elevational view thereof.

The locksets shown in the FIGS. 1, 2 and 3 are shown in broken lines for illustrative purposes only and form no part of the claimed design.

I claim:

The ornamental design for a display and demonstrator rack for cylindrical locksets and the like, as shown and described.
